AUTOMOBILE

Herbert F. Weissinger, Franklin, and George A. Schmidt, Detroit, Mich., assignors to Chrysler Corporation, Highland Park, Mich., a corporation of Delaware

Application June 11, 1956, Serial No. 41,863

Term of patent 14 years

(Cl. D14—3)

Fig. 1 is a perspective view from the side and slightly above of an automobile, showing our new design the side opposite being similar to the one illustrated;

Fig. 2 is a perspective view from the front portion thereof; and

Fig. 3 is a perspective view from the side and rear of the automobile.

The dominant features of our design reside in the portions shown by means of full lines in the drawing.

We claim:

The ornamental design for an automobile, substantially as shown and described.
